UNITED STATES PATENT OFFICE.

GEORGE G. GOING, OF MIDDLETOWN, CONNECTICUT, ASSIGNOR TO REMINGTON-NOISE-LESS TYPEWRITER CORPORATION, OF NEW YORK, N. Y., A CORPORATION OF NEW YORK.

TYPEWRITING MACHINE.

Application filed July 18, 1925. Serial No. 44,522.

My invention relates to guiding devices for use in typewriting machines, and the primary object of the invention is to provide new and improved guiding and controlling devices which are especially adapted for employment with what is known as the center-tie element of the No. 6 Remington-Noiseless typewriting machine, although it is to be understood that the principles of 10 the invention may be availed of in connection with other parts and in other styles of typewriting machines.

To the above and other ends which will hereinafter appear, my invention consists 15 in the features of construction, combinations of devices and arrangements of parts hereinafter described and particularly pointed out in the claims.

The present construction was designed 20 particularly for the purpose of holding the center-tie of the Remington-Noiseless machine so securely as to prevent it from being affected by the shocks and jars incident to the operation of the machine, while at the 25 same time guiding the center tie with accuracy and nicety in its fore-and-aft adjustments, which, as is well understood are for the purpose of varying the manifolding capacity of the machine. As heretofore constructed, the center-tie was controlled and guided in its fore-and-aft movements and 30 positions by seats cut or milled on the stationary parts, the main seat being in the cross bar at the rear lower portion of the machine, and the forward or upper seat being 35 in the type bar support. This construction required that the two seats should be in exact register in order to insure proper positioning and guiding of the center-tie element, and such exact registration was difficult 40 to obtain in practice. By my present invention the forward seat is dispensed with, only the main or lower seat being retained, but its construction being altered. In addition 45 to this lower seat or guiding device, another device for guiding and stabilizing the center tie is provided, said other device comprising retainers or arms which are adjustably secured to and project laterally 50 from the sides of the center-tie above its seat. These arms are provided with round holes or eyes and slidably engage pins or studs projecting forward from rectangular brackets which are adjustably secured to the

frame or a stationary part of the machine. 55 The arms or eye-parts and the brackets or stud-carrying parts are arranged in pairs, all of these parts being adjustable independently of each other so that the stud and eye-guiding devices may readily be brought into 60 register, so to speak, with the main guide or seat at the under side of the center-tie element. The construction permits fore-and-aft adjustments of the center-tie to be effected without the obstruction or friction 65 due to faulty registration of the seats or guides, while at the same time providing a support for the center-tie additional to the lower guide seat and some distance above the same and to the rear thereof, this location 70 being highly advantageous for stabilizing purposes. The preferred form of my invention is illustrated in and will be described in detail in connection with the accompanying drawings wherein— 75

Figure 1 is a fragmentary vertical sectional view taken fore-and-aft of the No. 6 Remington-Noiseless typewriting machine and illustrating the center-tie and associate parts, together with the guiding and controlling devices for the center-tie. 80

Figure 2 is a transverse vertical sectional view taken on a plane indicated by the section line 1—1 in Fig. 1 and looking in the direction of the arrows at said line. 85

Figure 3 is a fragmentary rear elevation partly in section showing certain of the novel guiding devices comprised in my invention. 90

Figure 4 is a vertical sectional view of a supplemental guiding device, the section being taken on a plane indicated by the section line 2—2 in Fig. 5 and looking in the direction of the arrow at said line. 95

Figure 5 is a fragmentary horizontal sectional view taken on a plane indicated by the section line 3—3 in Fig. 1 and looking downward, and 95

Figures 6 and 7 are perspective views of the novel center-tie retaining devices or guides. 100

As appears from Figs. 1 and 5, the main frame of the No. 6 Remington-Noiseless typewriting machine comprises side plates 1 which are connected at the front by a U-shaped portion (not shown herein) which serves to enclose the keyboard. At the rear the side plates are connected by a rear plate 105

2 which is secured at its ends by headed screws 3 to the rear vertical faces of the side plates 1. Screwed down on the upper faces of the side plates is a top plate which is fragmentarily shown in Fig. 1 and numbered 4. The frame of the machine further comprises a cross bar 5 which is disposed at the rear portion of the main frame between the side plates 1 to which the ends of the cross bar are suitably secured. Supported at the middle portion of the cross bar 5 is a type action segment 6 which provides one of the supports for the type actions of the machine. The segment 6 is horizontally disposed and is provided with two rearwardly extending arms 7 which receive headed screws 8 that are threaded downward into the cross bar 5 and secure the segment 6 fixedly thereto, assisted by dowel pins 9. As is plainly shown in Fig. 1 the segment 6 is in a plane above that of its supporting arms. The rear under face 10 of the segment is finished to provide a guiding or contact surface.

Supported on the main frame is a movable member or casting commonly called a "center-tie" and which, as a whole, is designated by the reference numeral 11. The member or center-tie comprises a cross bar or body portion 12 extending laterally outward to the sides of the machine and an upward extension 13 at the central rear portion of the body 12, this extension having side flanges or ribs and a cross web and being substantially U-shaped in cross section. The manner of supporting and guiding the center-tie on the main frame with which my invention is more particularly concerned will be described later. Projecting upward from the cross bar or body 12 are lugs 14 which provide bearings for a rock shaft or balancing shaft 15 near the ends of which are secured a pair of two-part carriage balancing levers 16. The forward arms of these levers are connected through trains of devices with the shift keys of the machine as fully disclosed in my prior application, Sr. No. 14,100, filed March 9, 1925. The rear arms of the levers 16 are pivotally connected at 17 with a carriage supporting trackway or rail comprised of two rigidly connected parts 18 and 19, forming a trough-like bar which is provided with oppositely disposed grooves receiving antifriction rollers 20, said rollers also cooperating with oppositely disposed grooves in a carriage cross-bar 21. Besides the cross bar 21 the carriage comprises end bars 22 fixed to and rising from the cross bar at its ends. Mounted on the carriage is a rotary platen 23 with the front face of which cooperate the printing instrumentalities or type bars. The platen 23 and one of the type bars 24 are diagrammatically illustrated in Fig. 1. It will be understood that when one of the shift keys is depressed, it will actuate the levers 16, causing their rear arms

to swing upward, raising the rail 18, 19, the carriage 21, 22, and the platen 23, the latter being thereby shifted to a new case position. This case shifting operation of the platen does not affect the member or center-tie 11 which remains quiescent during such operation. The carriage is connected with guiding devices which are controlled by a track-way formed in the center-tie extension 13, these guiding devices assisting to stabilize the carriage during its case shifting and other movements as explained in my prior application aforesaid.

The center-tie is adapted to be set variably in different positions in a fore-and-aft direction on the main frame in order to vary the vertical plane in which the printing face of the platen lies, so as to afford variation of the pressure with which the types co-operate with the printing face, thereby controlling the manifolding power of the machine, as is well understood. As heretofore stated, in the prior construction, the mounting of the center-tie was open to certain objections and it was for the purpose of overcoming these objections and otherwise improving the mounting and guiding of the center-tie in its fore-and-aft movements that my present invention was more particularly designed. To this end the middle portion of the bar 12 is provided with downward ribs or extensions 11^a which are virtually continuations of the flanges of the part 13. The ribs 11^a are finished at their under sides to provide guiding surfaces 25 and 26, these surfaces 100 contactively engaging with machined or finished surfaces 27 formed on the bar 12 between the two arms 7, as best appears in Figs. 1 and 2. It will be seen that the arms 7 co-operate with the top of the cross bar 12 to form a seat or depression in which the downward extensions 11^a are seated or engaged. The outer faces of the downward extensions and the inner faces of the arms 7 are machined or finished and co-operate to prevent undue lateral movement or yield of the lower portion of the center-tie, as will be clearly understood from Fig. 2. The under face of the segment 6 is provided between the arms 7 with a slight downward extension 28, the bottom face of which is finished or machined to provide a contact surface or stop with which contacts or engages the upper face of an extension or cross bar 11^b connecting the extensions or flanges 120 11^a, the upper face of the cross bar 11^b being likewise machined or finished. The construction described provides a main guiding device or seat for the lower middle portion of the center-tie.

Additional guiding and controlling devices of novel construction are provided for the center-tie in rear of and above the main seat just described. The novel devices aforesaid are most clearly illustrated in Figs. 3

to 7. They comprise pairs of members associated with the extension 13 of the center-tie. Each pair of said members comprises a right-angled arm or eye-member 29 formed at one branch 30 with two elongated holes or slots indicated at 31, one above the other. The other branch 32 of the arm 29 is formed with a round aperture or eye indicated at 33. Headed screws 34 pass through the slots 31 and adjustably secure the arms or eye-members 29 against the sides or ribs of the extension 13 near its lower end. These sides are formed with shallow slot-ways or depressions 35 in which the arms are received, the eye-bearing branches 32 projecting laterally outward from the sides of the extension 13. The slots 31 afford an upward and downward adjustment of the arms 29 so as to vary the up and down location of the eyes or apertures 33. Each pair of the aforesaid guiding devices is constituted by one of the arms 29 and a co-operating pin or stud-carrying member, these members each being designated as a whole by the numeral 36. Each member comprises a plate-like portion 37 which is formed with a pair of elongated screw holes or slots 38 and carries at its inner end a forwardly projecting pin or stud 39. The pin carrying members 36 are received in horizontal slot-ways 40 cut in the rear faces of upward extensions 41 on the frame plate 2. The screw holes 38 receive headed screws 42 which are threaded into the extensions 41 and rigidly secure the members 36 in place. The elongated holes 38 afford horizontal adjustments of the members 36, so that the pins or studs 39 may be moved inward toward each other or outward away from each other. This adjustment, it will be noted, is at right-angles to the up and down adjustments of the eye-members 29 with which the members 36 co-operate, the pins or studs 39 being received in the apertures or eyes 33 and having a sliding fit therewith. It will be understood that with the clamping screws 34 and 42 loose, the pairs of guiding members 29 and 36 are free to be properly registered with each other and also in relationship to the main seat at the under side of the movable member or center-tie.

The left-hand member 36 is provided with a forwardly projecting pin 43 (Fig. 6) which carries a flanged roller or spool 44 and also an angular guide 45 which is free to turn on the pin 43 and is formed with a guide slot 46 through which the band or tape that connects the carriage with the spring drum (not shown) passes, said tape also being confined between the flanges of the roller 44.

The guiding and controlling devices for the center-tie or element as above described are highly effective but it has been thought good practice to provide additional or sup-

plementary guiding or stop devices which are associated with the lateral extensions of the center-tie, that is, with the end portions of the cross bar 12. These supplementary devices as shown in Figs. 4 and 5 comprise screw stops 47 formed with heads 48 which are at the lower ends of the screw stops, these being threaded upward through the end portions of the cross bar 12, the nicks of the screws being at the tops or points of the shanks for convenience of adjustment. A check nut 49 holds each guide screw or stop 47, 48 in adjusted position. The bottom face of the head 48 is adapted to contact with the upper surface of a stationary rib or projection 50 formed on the associated end of the cross bar or frame part 5. It will be apparent that with one of these guiding or stop devices at each end of the center tie, undue tipping thereof will be prevented.

The center-tie as a whole is constantly urged rearward by spring devices comprising a pair of coiled draw springs 51 anchored at their rear ends to plates 52 that are perforated to fit over the tops of screws 53 that are threaded into the upper face of the rear plate 2. The screws 53 are provided with neck or narrow portions 54 with which the perforations in the plates 52 engage, and have hexagonal portions to facilitate adjustments. Similarly the forward ends of the draw springs 51 are connected to plates 55 perforated to fit over necked and headed screws 56 that are threaded into the top of the cross bar 12, and also have hexagonal body portions. The construction is such that the center-tie or movable member 11, together with the platen 23 and platen carriage 22 supported thereon, are constantly urged rearward.

The fore-and-aft or backward and forward movements of the variably settable element or center-tie are controlled by hand actuated devices comprising a push-and-pull link 57. The rear end of this link is received in a vertical kerf or slot-way 58 formed in an upwardly extending lug 59 integral with the middle portion of the cross bar 12 of the center-tie. A screw pin 60 bridges the kerf 58 and provides a pivot for the link 57 which is thus pivotally connected at its rear end with the center-tie. The link extends horizontally forward and has riveted or otherwise secured to its front end a screw 61. Threaded on this screw is a nut device 62 counter-sunk at its forward end portion as indicated at 63, the interior of the counter-sunk portion being likewise threaded to receive a headed screw 64. The screw 64 serves to secure against the head or flange 65 of the nut 62, the inner end of a crank arm 66, the outer end of said crank arm being provided with a hand piece or finger button 67. In order to prevent displacement between the nut 62 and the crank

arm 66 the opposing faces of the crank arm and of the flange 65 are fluted or otherwise suitably roughened so as to give full effect to the clamping action of the screw 64. The 5 crank arm terminates at its outer end in a pointer 66^a which co-operates with an indicating plate 68 that is secured by screws 69 to the downwardly extending flanged portion 4^a of the top plate 4; the screws passing 10 through washers or separators 70. As is well understood, the pointer and the plate 68, which is formed with a scale on its front face opposite the pointer, provide co-operating pressure-indicating devices which indicate 15 the location of the center-tie and the front or printing face of the platen in connection with manifolding operations. By manipulating the finger piece 67 the nut 62, 65 will be rotated or turned in one direction 20 or the other, thus drawing the screw 61 forward or permitting its movement rearward. These movements transmitted by the link 57 to the center-tie will either pull or draw the center-tie forward limited extents 25 in opposition to the springs 51 or permit it to be drawn rearward by said springs. Thus hand controlled movements in a fore-and-aft direction of the movable element or center-tie are afforded, resulting in 30 variable settings of the center-tie and of the platen. During such movements the center-tie will be guided by the seat at its under side and by the devices comprising the pairs of members 29 and 36 disposed to the rear 35 of and above the main seat. The construction is such that while fore-and-aft movements and re-settings of the center-tie are readily afforded, it will always be held by its guiding and controlling devices or means 40 in substantially rigid relationship with the main frame after such settings, the guiding devices being so disposed that shocks and jars incident to the endwise movements of the carriage and otherwise occurring during 45 the operation of the machine, will be withstood and taken up by the center-tie guiding and controlling means.

It will be seen that by my present invention there is provided in combination with 50 a movable element or member, in the present case a center-tie, two sets of guides therefor, one set comprising non-adjustable co-operating parts, and the other set comprising co-operating parts all of which are adjustable; that the two sets are spaced apart 55 or separated; that the set composed of adjustable parts is constituted by pairs of members, each pair being composed of a part carrying a pin or stud and a part 60 formed with an eye engaged by said pin; that the said pairs of guiding members are arranged at the rear of the movable element or center-tie and somewhat about the other set of guides which co-operate with the 65 under side of the element and comprise a

stationary seat therefor, said seat co-operating with the middle portion of the element; that said element is moved by hand-controlled means to vary the plane of the printing face of the platen and that the guiding surfaces or sets of guides are effective to maintain the element in a predetermined path during such movements and in the various positions in which it may be set as the result of such movements; that said guides assist said element to withstand displacement due to any shocks or jars which may occur during the operation of the machine and particularly during movements of the platen and carriage in a direction transverse to the fore-and-aft movements to which the element or center-tie is subjected.

What I claim as new desire to secure by Letters Patent is:—

1. In a typewriting machine, the combination of a movable carriage-supporting element, and two sets of guides therefor, one set comprising non-adjustable co-operating parts and the other set comprising pairs of variably contacting parts, each pair being constituted by an eye-part and a pin or stud part, the eye parts and the pin parts being adjustable at right angles to each other.
2. In a typewriting machine, the combination of a carriage-supporting element movable fore-and-aft of the machine, and two sets of guides therefor, one set co-operating with the under side of said element and the other set co-operating with the rear portion of said element above the other set and comprising co-operating parts all of which are adjustable.
3. In a typewriting machine, the combination of a carriage-supporting element movable fore-and aft of the machine, and two sets of guides therefor, one set co-operating with the underside of said element and the other set co-operating with the rear portion of said element above the other set and comprising pairs of variably engaging parts, said pairs being spaced apart and all of the members of the pairs being separately adjustable.
4. In a typewriting machine, the combination of a carriage-supporting element movable fore-and-aft of the machine and having lateral extensions, two sets of guides therefor, one set co-operating with the under side of said element and the other set co-operating with the rear portion of said element above the other set and comprising co-operating parts all of which are adjustable, and supplementary guides for said lateral extensions.

5. In a typewriting machine, the combination of a movable carriage-supporting element, said element being provided with an upward extension at its rear middle portion, and two sets of guides for said element, one set at the under side of said element and the

other set comprising pairs of engaging parts co-operative with said upward extension.

6. In a typewriting machine, the combination of a movable carriage-supporting element, said element being provided with an upward extension at its rear middle portion, and two sets of guides for said element, one set at the under side of said element and the other set comprising pairs of co-acting parts 5 at the sides of said upward extension, the parts of each of said pairs being independently adjustable.

7. In a typewriting machine, the combination of a movable carriage-supporting element, said element being provided with an upward extension at its rear middle portion and also with lateral extensions to the sides of the machine, two sets of guides for said element, one set at the under side of said 15 element and the other set comprising pairs of co-acting parts at the sides of said upward extension, and supplementary guides for said lateral extensions.

8. In a typewriting machine, the combination of a slidably mounted carriage-supporting element, guide members adjustably secured to and projecting outwardly therefrom, and other members having forwardly projecting pins that engage slidably in 20 apertures in said guide members, the pin-carrying members being adjustable on a stationary part of the machine.

9. In a typewriting machine, the combination of a movable carriage-supporting element, hand controlled means for variably setting said element in a direction fore-and-aft of the machine, and guiding devices for guiding said element and for maintaining it in its set positions, said guiding devices comprising members having horizontally projecting portions formed with apertures, said members being vertically adjustable on said element, and other members having forwardly projecting pins that are slidably engaged by said apertures, said pin-carrying members being so mounted on a stationary part as to afford adjustments of said pins toward and away from each other transversely of the machine.

10. In a typewriting machine, the combination of a platen, a platen carriage, an element on which said carriage is supported; said carriage being shiftable on said element to change case, hand controlled means for 55 moving said element fore-and-aft of the machine to vary the vertical plane of the printing face of the platen, and two sets of guides for said element, one set comprising non-adjustable co-operating parts and the other set comprising co-operating parts all of which are independently adjustable to afford take-ups both horizontally and vertically.

11. In a typewriting machine, the combination of a platen, a platen carriage, an element on which said carriage is supported,

hand controlled means for moving said element fore-and-aft of the machine to vary the vertical plane of the printing face of the platen, and sets of guides for said element, one set co-operating with the under side 70 thereof and the other set being arranged together and comprising pairs of eye and stud members, all of said members being independently adjustable.

12. In a typewriting machine, the combination of a platen, a platen carriage, an element on which said carriage is supported, hand controlled means for moving said element to vary the plane of the printing face of the platen, and two sets of guides for said element, one set being constituted by detachable parts and the other set being constituted by surfaces on the frame of the machine and co-acting surfaces on said movable element. 75

13. In a typewriting machine, the combination of a platen, a platen carriage, an element on which said carriage is supported, hand controlled means for moving said element to vary the plane of the printing face 80 of the platen, and two sets of guides for said element, one set being constituted by detachable parts and the other set being constituted by co-acting surfaces on the frame of the machine and on said movable element, said other set being effective to prevent displacement of said movable element when the detachable parts are removed from the machine. 85

14. In a typewriting machine, the combination of a platen, a platen carriage, an element on which said carriage is supported, said carriage being shiftable on said element to change case, hand controlled means for moving said element to vary the vertical plane of the printing face of the platen, and two sets of guides for said element, one set being constituted by detachable parts and the other set being constituted by a plurality of faces oppositely disposed on said movable element and corresponding oppositely disposed faces on the frame of the machine. 100

15. In a typewriting machine, the combination of a platen, a platen carriage, an element on which said carriage is supported, hand controlled means for moving said element fore-and-aft of the machine to vary the vertical plane of the printing face of the platen, and sets of guides for said element, one set constituted by a seat formed in a stationary part and by an oppositely faced stationary overhang, said seat and said overhang slidably co-operating with faces on said movable element. 115

16. In a typewriting machine, the combination of a platen, a platen carriage, an element on which said carriage is supported, hand controlled means for moving said element fore-and-aft of the machine to vary the vertical plane of the printing face of 120 125 130

the platen, said element having an upward extension at its rear middle portion and also having lateral extensions, sets of guides for said element, one set at the under side thereof, another set comprising pairs of slidably engaging parts arranged at the sides of the upward extension, and supplementary guides for the lateral extensions, both pairs of slidably engaging parts being adjustable to afford both horizontal and vertical take-ups, and the supplementary guides being relatively adjustable vertically.

17. In a typewriting machine, the combination of a platen, a platen carriage, an element on which said carriage is shiftably supported, a hand actuated threaded member, a link connecting said hand actuated member with said element for transmitting movement thereto in a direction fore-and-aft of the machine, and sets of guides for said element, one set comprising pairs of angular members seated in slots in said element and adjustably secured thereto, and stud-carrying brackets co-operating with apertures in said eye-members, said brackets adjustably seated in slots in a stationary part of the machine.

18. In a typewriting machine, the combination of a platen, a platen carriage, an element on which said carriage and platen are vertically shiftable to change case, hand controlled means for moving said element together with said platen and said carriage fore-and-aft of the machine to vary the vertical plane of the printing face of the platen independently of its case shifting movement, and sets of guides for guiding said element during its fore-and-aft movements, one set of guides co-operating with the under side of said element and the other set being arranged higher and comprising pairs of eye members and co-operating stud members.

19. In a typewriting machine, the com-

bination of a platen, a platen carriage, an element on which said carriage and platen are vertically shiftable to change case, hand controlled means for moving said element together with said platen and said carriage fore-and-aft of the machine to vary the vertical plane of the printing face of the platen independently of its case shifting movements, and sets of guides for guiding said element during its fore-and-aft shifting movements, one set of guides comprising a seat or depression in the framing of the machine beneath said element, the element being provided with faces slidably engaging with said seat, and the other set of guides comprising pairs of members arranged above the first set and to the rear thereof, each pair comprising a bracket carrying a stud and adjustably secured to the frame, and also an angular arm formed with an eye or hole in which the stud is received, said arm being adjustably secured to said member.

20. In a front strike typewriting machine, the combination of a platen, a platen carriage, a carriage rail on which said carriage runs, a center tie on which said rail is shiftably supported to enable the platen and carriage to be shifted independently of the center-tie to change case, hand connections for variably setting said center-tie fore-and-aft of the machine, and guides for controlling the movements of the center-tie during its movements, and for enabling it to withstand shocks sustained during the operation of the machine, said guides comprising a seat in the frame below the center-tie and also pairs of studs slidably engaging perforated members adjustably secured to the center-tie at its rear portion.

Signed at Middletown, in the county of Middlesex and State of Connecticut this 15th day of July, A. D. 1925.

GEORGE G. GOING.
